UNITED STATES PATENT OFFICE.

JOHN M. WAKEMAN, OF WATKINS, NEW YORK.

FIRE-ESCAPE.

SPECIFICATION forming part of Letters Patent No. 371,483, dated October 11, 1887.

Application filed June 2, 1887. Serial No. 240,043. (No model.)

To all whom it may concern:

Be it known that I, JOHN M. WAKEMAN, a citizen of the United States of America, residing at Watkins, in the county of Schuyler 5 and State of New York, have invented certain new and useful Improvements in Fire-Escapes; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

My invention relates to certain new and useful improvements in fire-escapes, the object of 15 my invention being to provide a means whereby persons can descend from buildings upon a single inclined rope, and while descending 20 can regulate the speed of their descent.

My invention consists of a fire-escape which is adapted to be used as a means of descent upon a single rope, the construction of the 25 same being such that a pulley which is carried thereby can clamp upon the rope so as to retard the descent; and with the above end in view my invention consists in the construction and combination of the parts, as will be hereinafter fully set forth, and specifically pointed 30 out in the claims.

In the accompanying drawings, which illustrate my invention, Figure 1 is a view showing the invention in use. Fig. 2 is an end view, partly in section. Fig. 3 is a detail perspective 35 view of the pulley detached, and Fig. 4 is a modification of my invention.

A refers to the rope, which is preferably of wire or finely-woven fiber, so as to be comparatively hard, which rope may be stretched from 40 the window of a building to the ground, and in connection with such a rope my invention is adapted to be used.

B refers to one of the bars or arms, which is provided at one end with a loop or eye, B', to 45 which a strap, b, is secured. The opposite end of the bar B is rounded and bent at right angles, as shown at C, and near the end the portion C is squared, as shown at c, the extreme end being screw-threaded for the reception 50 of a nut, D, which nut is rounded on its under side.

E refers to the hand-grasping bar, which is shorter than the bar B, the lower end being formed into a loop, as shown, while the upper end has a square opening, e, which is adapted 55 to fit loosely over the squared portion c, so that the same may be moved thereon.

The pulley, which is journaled on the bent end C of the bar B, is preferably made in two parts, as shown in Figs. 2 and 3, one part, F, 60 consisting of a hub, f, which is provided with a flange, f', the edge of which is bent outwardly. The hub f is provided centrally with a circular opening, and its edge is beveled from this opening toward the flanged portion, 65 as shown at f². The portion G of the pulley F has a central opening, g, of a little larger diameter than the diameter of the hub f, and its periphery is beveled, as shown.

When a solid pulley is used, as shown in 70 Fig. 4, the periphery is provided with a V-shaped groove, within which the rope will lie.

In practice the rope is first stretched and the parts are placed over the rope so that the same will lie between the flanges of the pulley, 75 and the person who is to descend first places the belt b around his body and grasps the loop. By drawing the looped hand-bar toward the bar B the hand-bar is caused to rock so as to move the flange G toward the flange f', thereby 80 clamping the rope between the flanges and creating sufficient friction to prevent too rapid descent. The rapidity of the descent can be regulated by hand-pressure.

I am aware that it has been proposed in constructing fire-escapes of this general character to journal the rope-pulley between the rigid arms of a U-shaped bracket, a hand-lever being pivoted to one of the arms of said bracket and provided with a forked end to straddle 90 said arm and bear upon one end of the pulley. My device differs materially from that mentioned, however, in that I employ a single bracket-arm of L shape, the roller being journaled on the short arm thereof, and clamped, 95 when necessary, between the long arm and a hand-brake secured upon the outer end of the short arm and extending down toward the loop at the end of the long arm B of the L-shaped bracket. Owing to this construction I effect a saving of material and labor, and aside from this provide a brake which will act 100

more promptly and effectually, as the clamping-pressure of arms B and E is exerted at the periphery of the pulley.

I claim—

5 1. In a fire-escape adapted for use upon a rope, a bar, B, provided with a bent end which forms a journal for a pulley, a hand-bar suitably attached to the bar B, so that by moving the hand-bar toward the same a brake will be 10 applied to the pulley, substantially as shown, and for the purpose set forth.

2. In combination with a bar, B, having a loop at one end for the attachment of a belt thereto, said bar being bent at its opposite end 15 so as to form a journal for a pulley, a looped hand-bar secured by a nut having a beveled face to the bar B, and a pulley located between said bars, substantially as shown, and for the purpose set forth.

3. The combination, in a fire-escape, of a pulley having a projecting hub with a beveled face, a flange, G, adapted to be placed over said hub, and a bar, B, one end of which is bent at right angles and provided with a squared portion for the reception of a brake-bar, and a nut having the inner face beveled for securing the parts to each other, the parts being organized so that the hand-bar operates as a brake, substantially as shown, and for the purpose set forth. 20 25 30

In testimony whereof I affix my signature in presence of two witnesses.

JOHN M. WAKEMAN.
